WATER SPRINKLING DEVICE

Filed Jan. 7, 1926

Inventor:
Fingal C. Orr.
By Martin P. Smith, atty.

UNITED STATES PATENT OFFICE

FINGAL C. ORR, OF ROSEMEAD, CALIFORNIA

WATER-SPRINKLING DEVICE

Application filed January 7, 1926. Serial No. 79,734.

My invention relates to a sprinkler or water distributing device of the rotary arm type, such as is disclosed in my prior Patent No. 1,649,179.

5 In the form of rotary sprinkler disclosed in my aforesaid co-pending application, a horizontally disposed tubular arm is provided at one end with a jet nozzle and this arm is mounted to rotate on a vertical axis. 10 The power necessary to cause the arm to rotate, is obtained by the reactive force of the water discharging from the nozzle, it is the purpose of my present invention to provide simple and efficient means for utilizing impact or impinging force of the water jet that discharges from the nozzle against a relatively small fixed member for overcoming the starting inertia of the horizontally revolving arm in order that the latter may freely rotate with a relatively slow erratic or step-by-step movement and thus distribute the water that discharges from the jet nozzle throughout a considerable area in all directions from the rotary sprinkler arm.

15 20 25 Further objects of my invention are, to provide an attachment for the spray nozzles of water sprinklers that may be economically produced and installed, capable of ready adjustment to suit different conditions and, further, to provide a device of the character referred to that will be very effective in performing its intended functions.

With the foregoing and other objects in view, my invention consists in certain novel features of construction and arrangement of parts that will be hereinafter more fully described and claimed and illustrated in the accompanying drawings in which:

30 35 40 Fig. 1 is a side elevational view of a rotary sprinkler arm, the jet nozzle of which is provided with an attachment embodying my invention.

45 Fig. 2 is a section taken lengthwise through the jet nozzle of a rotary sprinkler and showing the attachment applied thereto.

50 Fig. 3 is a sectional view taken through the end of a jet nozzle and showing a modified form of the attachment.

55 Fig. 4 is a sectional view taken through the central portion of a jet nozzle and showing a further modified form of the attachment.

Fig. 5 is a plan view of the form of device seen in Fig. 4.

Fig. 6 is a sectional view taken through a central portion of a jet nozzle and showing a further modified form of the attachment.

Fig. 7 is a plan view of the end portion of a jet nozzle and showing a further modified form of the attachment.

60 Fig. 8 is a vertical section taken approximately on the line 8—8 of Fig. 7.

65 Referring by numerals to the accompanying drawings and particularly to the construction illustrated in Figs. 1 and 2, 10 designates a vertically disposed water pipe that is provided at its upper end with a vertically arranged bearing 11 for a horizontally disposed tubular sprinkler arm 12.

70 75 Mounted for rotary movement on one end of the main arm 12 is a small auxiliary sprinkler arm 13, and detachably applied to the other end of the main sprinkler arm 12 is a jet nozzle 14.

75 80 85 The outer portion of sprinkler arm 12, or that portion carrying the jet nozzle 14, occupies an upwardly inclined position of approximately 15° or 20° relative to a horizontal plane and when the sprinkler is set up for use, the arm 12 is rotated to a slight degree in either direction so that the inclined outer end portion thereof occupies a slightly angular position relative to the vertical plane occupied by the axis of the sprinkler arm.

85 90 Thus the water issuing from the jet nozzle 14 has a certain degree of reactive force which tends to rotate the arm 12 on its axis, but the lateral angular position of the outer portion of the arm is insufficient to permit the small degree of reactionary force of the jet of water to effect rotation of the sprinkler arm. In other words, the reactive force of the jet tends

95 100 to rotate the sprinkler arm, but the friction that exists in the bearing 11 of said rotary arm holds the latter against rotation against the reactive force of the jet.

Secured in any suitable manner to the outer end portion of the jet nozzle, is one end of a section of wire that is bent to form an inverted U-shaped member 15, the outer leg 16

of which occupies a plane at right angles to the axis of the jet nozzle 14 and the end of this leg is pointed as designated by 17. This pointed end occupies a position so that it projects into the stream or jet that issues from the jet nozzle and, as a result of the impact of the water with the pointed end 17, a sufficient degree of vibration is set up and maintained while the stream of water is issuing from the jet nozzle, to overcome the starting inertia of the arm 12 and thus said arm will as the inertia is overcome start and slowly rotate in its bearing and which rotation will be erratic or intermittent due to the gradual stopping and starting of said arm.

In the form of attachment illustrated in Fig. 3, the inverted U-shaped section of wire 18, is secured to nozzle 14 by means of a set screw 19, and the end of said member 18 that is adapted to be engaged by the stream or jet of water, is provided with a small spherical member 20, which, when the device is in use, projects a short distance into the stream or jet of water.

In the modified construction illustrated in Figs. 4 and 5, the attachment 21 is formed of a section of wire bent to form an inverted U-shaped member, one end of which is provided with an integral plate 22, through which passes a screw 23, and the latter being seated in the end of the jet nozzle. This construction enables the pointed end of member 21 to be adjusted across or transversely of the stream or jet of water that issues from the jet nozzle, thus varying the degree of produced vibration and reaction.

In the modified construction illustrated in Fig. 6, a lug 24 projects from the end of the jet nozzle and seated in a threaded aperture 40 in said lug is a screw 25 having a pointed end 26, and said screw carrying a lock nut 27, whereby the screw may be locked in its adjusted position.

In this form of device, the pointed end of the screw that engages the stream or jet of water may be adjusted toward or away from the axis of said stream or jet so as to produce a greater or less degree of vibration.

In the modified construction illustrated in Figs. 7 and 8, a split lug 28 projects from the end of the jet nozzle and clamped in said split lug is one end of a section of resilient wire, that is bent to form a large bow or U-shaped member 29, the free end of which is pointed as designated by screw 30, and which pointed end, when the device is in use, projects a slight distance into the stream or jet of water issuing from the jet nozzle.

In this form of device, the resiliency in the wire from which member 29 is formed, permits the pointed end of the attachment to vibrate as a result of the force of the water against said pointed end, and this vibratory action is sufficient to overcome the starting inertia of the rotary arm, and as a result, the

latter will rotate with a slow intermittent movement.

My invention involves the accepted principle in physics; that a greater force is required to start and move a body from a position of rest, than is required to keep said body in motion after it has been started and acquired a certain degree of momentum or inertia.

Thus, in my invention, I utilize the force of the jet of water for producing sufficient vibration to overcome the starting inertia of the rotary arm and thus the latter is caused to rotate with a slow step-by-step movement, which is the ideal condition for distributing water throughout the area covered by the sprinkler.

The auxiliary sprinkler arm 13 in operation tends to impart rotary motion to the main sprinkler arm 12 through reactive forces developed while said auxiliary arm is in operation and likewise when the arm 12 is slightly rotated in either direction to shift the angular position of the bent outer portion of said arm to one side or the other of a vertical plane so as to determine the direction of rotation of the sprinkler the water issuing from the jet nozzle 14 will develop a small amount of reactive force, but both this force and the reactive force developed by the auxiliary sprinkler 13 are not sufficient to overcome the starting inertia of the sprinkler arm and thereby cause the arm to rotate as a result of the combined reactive forces. By mounting a member on the nozzle and permitting said member to project into the jet of water issuing therefrom, a sufficient amount of vibration is developed to overcome the starting inertia of the sprinkler arm and thus in operation the same will slowly rotate and produce the desired results.

If, without any vibration producing means, the sprinkler arm is adjusted so that only reaction of the water jet is effective in rotating said arm, then, after the starting inertia has been overcome, the reactive forces will be too great and the sprinkler arm will be rotated at too great a speed to be effective, or to produce the desired results.

Thus it will be seen that I have provided a relatively simple and practical attachment that may be readily applied to the jet nozzles carried by rotary arm sprinklers and which attachment will be effective in utilizing the force of the jet of water issuing from the nozzle of the sprinkler to cause the rotary arm to slowly rotate with an intermittent or erratic movement and, as a result, a definite area of the ground surrounding the rotary arm sprinkler will be thoroughly sprinkled by the water issuing from the jet nozzle.

Obviously, minor changes in the size, form and construction of the various parts of my improved water sprinkling device may be made and substituted for those herein shown

and described without departing from the spirit of the invention, the scope of which is set forth in the appended claims.

I claim as my invention:

- 5 1. The combination with a tubular sprinkler arm mounted to rotate in a horizontal plane and provided at one end with a jet nozzle and at the opposite end with a rotating reactionary jet nozzle, which jet nozzles are
- 10 normally incapable of imparting rotary movement to said tubular arm, of a member secured to the end of said jet nozzle and having an arm that is disposed substantially at right angles to the axis of
- 15 said jet nozzle the free end of which arm occupies a position in the path of travel of the jet of water that issues from said jet nozzle.
- 20 2. The combination with a tubular sprinkler arm mounted to rotate in a horizontal plane of a reactionary jet nozzle mounted for rotary movement upon said sprinkler arm but normally incapable of imparting rotary movement to said tubular arm, a jet nozzle carried by said tubular arm on the opposite
- 25 side of its axis from the reactionary jet nozzle, and means carried by said jet nozzle and projecting substantially at right angles into the jet of water issuing therefrom for developing sufficient vibration to overcome the
- 30 starting inertia of said sprinkler arm.

In testimony whereof I affix my signature.
FINGAL C. ORR.
